8 Claims. (Cl. 263—3)

The invention relates to methods and apparatus for threading wires in muffles.

More particularly, the invention relates to furnaces equipped with muffles and designed for treating wire. The furnaces may provide a heat treatment process or a metallization process in which the wires to be treated are received in tubular muffles the diameter of which is very small in relation to their length. The furnaces are intended for operation in continuous fashion, however, a threading problem arises periodically each time work is resumed or after a wire breaks accidentally.

The threading method commonly employed is a manual one and consists, generally, in using several men at once to push the wire as fast as possible by hand until it emerges at the downstream end of the tube. This is a laborious method requiring personnel for the purpose; it is furthermore unreliable in the case of tubes exceeding a certain length and becomes entirely inapplicable where excessively long installations are involved.

It may even be said that the development of installations of great length (which would permit high-speed treatment) has been restricted by the impossibility of threading wires therethrough, since, in such furnaces, the wire soon heats up and softens on being introduced, then buckles under the thrusting force exerted, finally creating an obturation.

With a view to overcoming such drawbacks, the invention has for one of its objects a method whereby the threading of a wire through a muffle is accomplished by high speed mechanical propulsion, this speed being greatly in excess of the normal rate of travel of the wire in the course of treatment and being such that the wire has virtually no time to heat up other than superficially, the core of the wire retaining the mechanical properties needed to ensure stiffness.

The invention further has for its object apparatus for practicing such a method, and, in a preferred embodiment of such apparatus, high speed propulsion of the wire is accomplished by means of a pair of clamping rollers which are movable relative to each other to enable wire engagement to take place, said rollers being associated to at least one motor and to means for synchronizing their motion.

In the case of a furnace comprising a plurality of tubular muffles, the assembly consisting of the propelling rollers and their driving and synchronizing means is mounted in the form of a mobile and retractable mechanism, together with locking means whereby said mechanism may be clamped in position opposite a given tubular muffle, the retractability feature enabling the positioning to be accomplished without interfering with the neighbouring muffles.

The description which follows with reference to the accompanying drawing, given by way of example only and not of limitation, will give a clear understanding of how the invention may be performed.

In the drawing,

FIG. 1 is a front elevation of the wire threading device.

FIG. 2 is a side elevation of the device of FIG. 1.

FIG. 3 is a plan view of the device of FIG. 1.

2

FIG. 4 is an edgewise view of the threading rollers of the device showing their synchronizing gears, and

FIG. 5 is a partial schematic perspective view of a heat treatment furnace with a cut away portion showing the muffles. FIG. 5 is on a reduced scale when compared with FIGS. 1-4.

Onto the front face 1 of a heat treatment furnace 1a open tubes 2a are arranged in single or multiple rows with front openings 2, and there is secured to this face 10 a supporting frame 3 which surrounds the front openings of said tubes. The tubes 2a extend through a heat treatment zone in the furnace 1a. Said frame 3 has two reinforcing parallel stays 4 and 5 which extend perpendicular to the plane of the frame. These stays are joined together, on the one hand, by a round shaft 6 at the top and are joined, on the other hand, to a square shaft 8 having cylindrical end trunnions, said square shaft 8 being rotatable by means of a stud 9 rigidly connected to each of its ends, each such stud being designed to cooperate with a tubular manipulating rod.

The cylindrical shaft 6 is fixed between the stays 4 and 5. Protective casing 10 is coupled to shaft 6 so as to be pivotable thereabout while being slidable along shaft 6 coupled to the outer face of casing 10 is a lever 25 arm 11 supporting on its end a counterweight 12. Said casing encloses an upper grooved roller 14 mounted on a shaft 13, adjacent which is arranged a large-module gearwheel 15. Shaft 13 is the drive shaft of a compressed air motor 16 the casing of which is fixed to the side of casing 10, and compressed air motor 16 is equipped with a cock 17 which is connected to a flexible supply lead 18.

A cylindrical rod 19 is located beneath the shaft 6 and is slidable in bearings in the stays 4 and 5, one of these bearings comprising a spring-loaded ball type lock 20 designed to cooperate with grooves 21 on said rod 19 and spaced at intervals equal to those separating the tubes 2. Said rod 19 is provided with an operating handle 22 at each end.

40 A casing 23 is fixed rigidly to said rod 19, and this casing is similar to the aforementioned casing 10. Casing 23 encloses a roller 24 identical to roller 14 and an associated gearwheel 25 identical to gearwheel 15, the assembly being mounted loosely on a shaft 26 passing through casing 23.

The forward portion of casing 23 comprises, at a level corresponding to a plane approximately tangential to said roller 24, a bracket 23a on which are mounted two guiding rollers 27 which are freely rotatable about their respective axes. The bottom of casing 23 is designed to cooperate with a positioning strip 28 rigidly connected to the square shaft 8, and strip 28 cooperates at its extremities with limit stops 29 and 30 provided at the vertical ends of the stays 4 and 5 as best seen in FIG. 2.

55 The device described hereinabove functions in the following manner:

The bottom casing can be moved when in the lowered position shown by the chain-dotted lines in FIG. 2, to a position opposite one of the tubes 2 through which the wire is to be threaded. The bottom casing 23 is moved by a transverse sliding motion underneath the loom of wires running through the adjacent tubes 2 so as not to interfere with the passage of the wires through the adjacent tubes. When the bottom casing is opposite the tube 60 through which the wire is to be threaded, movement is stopped and transverse motion is prevented by the spring-loaded ball 20 as it drops into the corresponding groove 21 of shaft 19. The casing 23 is then raised by swivelling the strip 28. Having thus been lifted by the strip 28, the casing 23 is retained against the stop 30. With the casing 10 in the raised position shown in chain-dotted lines in

FIG. 2, an auxiliary wire contained on a small bobbin close to the installation (not shown) is placed in the groove of roller 24 and introduced, with its end preferably looped back, into the tube 2 to be threaded.

The counterweight 12 is then moved into transverse alignment with casing 23 and then pivoted downwardly to assume the position shown in solid lines in FIG. 2. In the latter position, the roller 14 clamps the wire against the roller 24 and the gearwheels 15 and 25 mesh together.

The cock 17 is then opened and the wire is driven through the tube 2, preferably with uniform acceleration, particularly in cases involving the heat treatment of a metal wire, although the invention is by no means limited thereto.

The compressed air motor 16 prevents any sudden increases in the speed of the wire, any slip between the rollers 14 and 25 and the wire, and any danger of the auxiliary wire being tightened about its bobbin. The threading operation is accomplished at high speed, e.g., in an installation 50 metres (164 feet) long threading is completed at an average speed of about 150 metres (492 feet) per minute. At such a speed heating up of the auxiliary wire in a tube 2 can only affect the wire superficially, so that its mechanical characteristics, insofar as its resistance to buckling is concerned, remain virtually unimpaired.

The threading operation having thus been accomplished easily and without any personnel other than a single operator, the end of the auxiliary wire can be joined to the wire to be treated. The threading mechanism can then be opened and retracted sideways, after which drawing of the wire to be treated through tube 2 can be performed by any conventional means.

It should be noted that both the retracting and the moving-into-position operations of the threading mechanism is performed clear of the loom of wires being treated in tubes 2.

The large-module gearwheels 15 and 25 are but a convenient means of synchronizing the rollers and avoiding buckling due to differences in speed from one roller to another. Alternatively, an individual motor could be provided for each roller. Similarly, the compressed air motor could be replaced by a motor of any type whatsoever, for instance an electric motor, certain motors of this type being capable of driving the system at uniformly accelerated speed.

In place of the counterweight 12, elastic means such as springs could be used for clamping the rollers together.

A cock incorporating a timing device could also be provided to shut off the supply of compressed air after a pre-set threading time.

It is indeed clearly apparent that, without departing from the scope of the invention, many modifications may be made to the specific embodiment described hereinbefore.

What I claim is:

1. A process for simultaneously treating a plurality of wires by concurrently passing the wires through a treatment zone at a predetermined speed, the step of initially threading one of said wires, comprising mechanically engaging said one wire at an end thereof in selective fashion while avoiding the other wires, passing said one wire through said zone independently of the other wires at a speed greatly exceeding that of the other wires so that

said one wire leaves said treatment zone with substantially unimpaired mechanical properties and reducing the speed of passage of said one wire through said treatment zone to that of the other wires when the one wire extends through said treatment zone.

5 2. Apparatus for threading a wire through a heated treatment zone, the apparatus comprising means defining said treatment zone, said means being provided with a plurality of openings equally spaced along a line to permit passage of a plurality of said wires through said zone, means selectively movable to each of said openings in a manner avoiding the other of the openings whereby the latter said means can be moved past openings through which wires are passing while avoiding said wires, said latter means being engageable with one of said wires in driving relation, means for driving said latter means in accelerating fashion and at a speed sufficient to cause passage of said wire through said treatment zone so that mechanical strength properties of said one wire are substantially unaffected by passage through said treatment zone, a pair of parallel shafts, each being on either side of said line of openings, and means for supporting one of said shafts from said means defining said treatment zone for movement along the line of said opening in lockable intervals corresponding to the spacing of said openings.

10 3. Apparatus as claimed in claim 2, wherein said means engageable with said wire includes a pair of rollers, each being supported for pivotal movement by one of said shafts.

4. Apparatus as claimed in claim 3 wherein the means for driving the rollers includes means synchronizing the drive thereof, and a motor operatively coupled to one of the rollers in driving relation.

15 5. Apparatus as claimed in claim 3 comprising means coupled to each of said rollers for causing pivotal movement thereof about the corresponding shaft between positions corresponding to engaged and disengaged positions for said wire.

6. Apparatus as claimed in claim 4 wherein the means synchronizing the drive of the rollers includes a pair of gearwheels, each being rigidly coupled to one of said rollers and in meshing engagement with the other gearwheel with the rollers in position corresponding to said engaged position.

20 7. Apparatus as claimed in claim 2 wherein said means for supporting said one shaft includes retractable stops for releasably locking the one shaft in positions corresponding to the openings.

8. A process as claimed in claim 1 wherein said passing of said one wire through said treatment zone is made by applying a substantially constant acceleration to said one wire.
